ATTORNEY

UNITED STATES PATENT OFFICE.

WILLIAM ZELLNER, OF PATERSON, NEW JERSEY.

STEAM-GENERATOR.

SPECIFICATION forming part of Letters Patent No. 313,270, dated March 3, 1885.

Application filed October 9, 1884. (No model.)

To all whom it may concern:

Be it known that I, WILLIAM ZELLNER, a citizen of the United States, residing at Paterson, in the county of Passaic and State of New Jersey, have invented a new and useful Improvement in Steam-Generators, of which the following is a specification, reference being had to the accompanying drawings, forming a part thereof, in which—

10 Figure 1 is a vertical longitudinal section, and Fig. 2 a transverse vertical section, of a fire-box embodying my improvements.

This invention relates to certain improvements in steam-generators for which Letters 15 Patent of the United States were granted to me May 8, 1866, No. 54,654.

In my former Letters Patent referred to that portion of the boiler containing the heating-tubes extends backward into the fire-box for 20 the purpose of increasing the heating-surface and distributing the heat therein, and such arrangement is included in my present invention, together with certain changes and additions in details of construction, which I will 25 first proceed to describe, and subsequently to point out the novel features thereof in the claims.

In the drawings, A represents the shell of a boiler; B, the fire-box, and C the fire-tubes, 30 that project about midway into the fire-box and are secured to a depending tube-sheet, a, the same as referred to in my former Letters Patent.

To the lower end of the depending tube-sheet a, I connect an inclosing-sheet, b, and extending at an obtuse angle therewith to the front water-leg of the fire-box, as shown in Fig. 1. In my former Letters Patent referred to the inclosing-sheet b extends at right angles to the tube-sheet and parallel with the fire-tubes, forming beneath it a fire-chamber rectangular in section, which in practice has a tendency to "huddle" the gases and deflect the same horizontally toward the fire-door. 40 Such construction in form also lacked a comparative degree of strength. The inclination given to the sheet b not only allows the gases to pass freely upward, but directs them to all parts of the crown-sheet and to fill the entire 45 upper portion of the fire-box, as indicated by the arrows, Fig. 1. The inclined position of

the sheet b also acts to brace the respective parts to which it is joined and make room for the transverse re-enforcing bars d, without interfering with the fire-tubes. The re-enforcing bars d are composed of parallel plates, between which "crow-foot" bolts are passed, that secures said plates together and to the sheet b. These bars are also shown, and have heretofore been applied, to the crown-sheet of the 55 fire-box, but only secured thereto and at one side of the shell of the boiler. In the present invention I have extended the same entirely across and secured both ends to the boiler-shell, thereby bracing the latter. The sheet 60 b is given an easy bend at its junction with the depending tube-sheet a, so as to offer no obstruction to the passage of the gases and to avoid weakening in bending. The bars d, above the fire-tubes, are provided with curved 65 diverging braces d', which extend from them to the outer shell of the boiler. The strengthening-bars d', attached to the top of the inclined sheet b, are provided with similar braces, d'', which extend from said bars d' to the sides 70 of the inner shell of the boiler. These braces d' d'', with said bars d', greatly strengthen 75 the said shells. The inner faces of this boiler are plane, and not spherical or curved. The inclined sheet b will not operate to huddle the 80 products of combustion or cause them to converge, as it would if said inclined part were curved in cross-section. The air-inlets e are located below the lower end of said inclined sheet b.

I am aware that it is not new to extend fire-tubes into the combustion-chamber of a cylindrical boiler and provided with an inclined shell extending below them, the inner faces of the various parts of the boiler being curvi- 85 linear.

I am further aware that it is not new to provide the crown-sheet of a fire-box with strengthening-bars, which are fastened to said crown-sheet and to the shell or casing of the 90 boiler. These constructions, therefore, I do not claim.

What I do claim, and desire to secure by Letters Patent, is—

1. In combination with the crown-sheet of 95 a fire-box and the outer shell of the boiler, a series of strengthening-bars, d, attached both

to said crown-sheet and shell, and two or more diverging braces, d^2 d^3 , attached to said strengthening-bars at their inner ends and to said boiler-shell at their outer ends, substantially as and for the purpose set forth.

5. 2. A series of fire-tubes, C, extending into the fire-box and provided with a plane inclined inclosing-sheet, b, in combination with strengthening-bars d^4 , arranged above said inclined sheet, and braces b^3 , which connects said bars with said sheet, substantially as set forth.

3. The tubes C, fire-box B, and tube-sheet a , in combination with inclined sheet b , curved at d^4 , where it is joined to said tube-sheet, substantially as set forth.

WILLIAM ZELLNER.
